Harold Dickey, Frank H. Smith
ATTORNEYS.

UNITED STATES PATENT OFFICE

GEORGE F. HUGHES, OF DETROIT, MICHIGAN, ASSIGNOR TO HERRON-ZIMMERS MOULDING COMPANY, A CORPORATION OF ILLINOIS

MEANS FOR SECURING SCREENS TO RADIATORS

Application filed January 24, 1931. Serial No. 511,077.

My invention relates to radiator guards and particularly to means for securing a guard or screen grille to a radiator.

When a screen grille or guard was to be attached to an automobile radiator or its enclosing shell, considerable difficulty was experienced in retaining the guard in fixed position relative to the radiator without harming the radiator cells or destroying the finish on its shell.

In practicing my invention I overcome the above difficulties by providing an anchor nut with an overlap flange which engages the underside of the edge of the inwardly disposed portion of the shell to constitute a support into which a guard retaining screw is secured. A plurality of these screws and anchor nuts are provided at predetermined points about the periphery of the guard for drawing it tightly against the radiator shell as the screws are forced into the anchor nuts. Blocks of rubber or like material are secured along the inner periphery of the guard for abutting against the front surface of the shell and preventing the marring of its finish. Projections are provided on the bottom blocks for engaging the inner portion of the radiator shell, for supporting the weight of the guard and preventing its downward movement.

Accordingly, one object of my invention is to provide a plurality of anchor bolts, for a guard of a radiator shell, with projections which shall engage the inner edge of the shell and firmly retain the guard against the front face thereof without requiring the shell to be drilled or distorted.

Another object of my invention is to provide an anchor bolt of the above described type, for a guard or screen grille of a radiator shell with a screen engaging member which shall fit between the mesh of the screen and shall be substantially invisible from the front of the guard.

A still further object of my invention is to provide the inner periphery of a guard for a radiator shell having anchoring means for drawing the guard tightly thereagainst, with rubber blocks, the bottom ones of which have projections which rest upon the inner surface

of the radiator shell for supporting the guard against downward movement.

A still further object of my invention is to provide retaining means for a screen grille or guard of the above mentioned type which shall be universal in application, easily attachable and economical of manufacture.

Numerous other objects or features of novelty of my invention will be either specifically pointed out, or will become apparent, when referring for a better understanding of my invention, to the following description in conjunction with the drawings, wherein:

Figure 1 is a front view, partly in section and partly in elevation, of a radiator guard embodying features of my invention.

Figure 2 is an enlarged perspective view of the anchoring means employed with the guard shown in Figure 1.

Figure 3 is an enlarged sectional view of the structure shown in Figure 1 taken along the line 3-3 thereof.

Figure 4 is an enlarged sectional view of the structure shown in Figure 1 taken along the line 4-4 thereof, and

Figure 5 is a broken sectional view of the structure shown in Figure 2 taken along the line 5-5 thereof.

My invention comprises, in general, a guard or screen grille 10 which includes a metal screen 11 which is cut to conform to the shape of the radiator shell and which is provided along its outer edge with a metal binding or frame 12. The guard, thus provided, is firmly retained on a shell 8 of a radiator 9 by clamping members 13 and projecting members 19, which will now be described in detail.

In Figure 2 I have shown an enlarged view of the clamping members 13 which comprise a nut 14, a screw 15 and a screen engaging member 16. The nut 14 includes a threaded shank portion 17 and an overlap flange portion 18 which is bent backwardly to constitute a projection which engages the under surface of the inner portion of the radiator shell, as shown in Figure 4. The nut 14 is preferably formed from a sheet of metal which is bent around a die in such manner as to have the thread thereon stamped into the

inner surface the shank 17 or the shank 18 may be formed about a cylindrical rod and the threads cut therein in a well known manner. It is to be understood that other methods, well known in the art to be suitable for constructing a nut with a flange, fall within the purview of my invention.

A screen engaging member 16 comprises a substantially square body portion 20 which fits downwardly between the wires of the screen and which is provided on two of its opposite ends with upturned flanges which are bent outwardly and backwardly to constitute inwardly presenting channels which engage adjacent elements of the screen. The base portion 20 is provided with a central hole 22 which is drawn outwardly to effect a recess for receiving the head of the screw 15. The hole 22 and the recess 23 are more clearly shown in the sectional view of Figure 5. In this construction the screw head extends below the surface of the screen and as the screen is engaged only at an adjacent pair of wires, the head and the screen-engaging element are substantially invisible from the front of the screen.

I provide a plurality of rubber blocks 24 on the inner periphery of the frame 12 to prevent the marring of the finish on the surface of the radiator shell 8 when the frame is held thereagainst by the anchor members 13. The blocks are attached to the frame in such manner that the ends thereof extend beyond a flange 27 on the frame and thereby retain the metal portions of the guard from contacting with the shell. Any suitable means may be employed for attaching the blocks to the frame and, for the purpose of illustration, I have shown a channel-shaped strip which is attached to the inner surface of the flange 27, forming a rectangular aperture in which the blocks 24 are supported and retained by their own resiliency.

The members 19, which support the weight of the guard or screen on the bottom of the shell, are similar in construction to the block 24 and, as shown more clearly in Figure 3, comprise resilient members 25 made of rubber or other suitable material. The members 25 are retained on the inner, lower edge of the frame 12 by means of clips 26 which are bolted, welded, brazed or otherwise attached to the inner surface of the flange 27 to firmly retain the member 25 thereon. The members 25 project beyond the flange 27 and are provided with a contour substantially similar to that of the inner portion of the radiator shell to thereby firmly engage the shell and support the weight of the guard. The clips 26 may be provided with extending portions 28 at the top, for the purpose of bracing and strengthening the projecting portions of the supporting members 25.

When my guard is to be attached to an automobile radiator the flanges 18 of the

anchor nuts 14 are first positioned under the inner edge of the radiator shell 8, as shown in Figure 4, in a position thereon substantially opposite to the screws 15 and the engaging members 16 associated with the screen. The guard or screen is then mounted against the face of the radiator shell with the blocks 24 engaging the front surface of the shell and the projections on the members 25 engaging the lower portion thereof to prevent the guard from contacting directly with the shell 8 from moving downwardly because of its weight. The screws 15 are then screwed into the nuts 14 and the screen is drawn tightly against the radiator shell with the flange 27 of the frame 12 spaced from the surface of the shell throughout its entire periphery by the blocks 24 and members 25 as mentioned above.

The screen 11 in its preferred form, as shown in the drawings, is made from heavy gauge, double-crimped wire well known in the art. It is to be understood, however, that any other type of screen, such as that made from expanded metal may be substituted therefor in which case the screen engaging member 16 is shaped to conform to the shape of the mesh of the substituted screen.

It will thus be seen that I have provided anchoring means for a guard, or screen grille, of a radiator which retains it in firm, fixed relation to its shell without requiring the drilling of the shell or causing the distortion of its edges or the marring of its surface. The anchoring means is universal in application being capable of engaging the inner edge of any radiator shell independently of the radiator. It is to be understood that the anchoring means is not limited to guards or screen grilles but may be employed for other purposes such, for example as attaching a winter-front to the radiator shell.

While I have described and illustrated but a single embodiment of my invention it will be apparent to anyone skilled in the art that many changes, omissions, additions and substitutions may be made therein without departing from the spirit and scope of my invention as set forth in the accompanying claims.

I claim as my invention:

1. Anchoring means for supporting a member on an automobile radiator shell which comprises a nut having a flange for engaging the inner edge of said radiator shell and a screw extending through said member for registering with said nut and drawing the member into engagement with said shell.

2. A guard for a radiator comprising a screen which is provided with supporting means including an anchor nut and screw for clamping the guard on the radiator shell independent of the radiator core and projecting members which register with the shell for

supporting the guard against downward movement.

3. An anchor means for supporting a screen on an automobile radiator shell comprising a nut having a flange for engaging the inner edge of the radiator shell, a screen engaging member having an aperture therein and a screw extending through said aperture and engaging said nut for drawing said screen into firm engagement with said shell.

4. An anchor means for supporting a screen on an automobile radiator shell comprising a nut having a flange for engaging the inner edge of the radiator shell, a screen engaging member having an aperture therein, a screw extending through said aperture and engaging said nut for drawing the screen into firm engagement with said shell and projecting members on the bottom of said screen and resting on said shell for supporting the weight of the screen against downward movement.

5. Anchor means for supporting a screen on an automobile radiator shell comprising a nut having a flange for engaging the inner edge of the radiator shell, a screen engaging member comprising a body portion extending between the wires of a screen and provided with inwardly presented channels for engaging the wires of said screen and a screw extending through said body portion and engaging said nut for drawing said screen into firm engagement with said shell.

6. An anchor means for supporting a screen on an automobile radiator shell comprising a nut having a flange for engaging the inner edge of the radiator shell, a screen engaging member comprising a body portion extending between the wires of a screen and provided with inwardly presented channels for engaging the wires of said screen, a screw extending through said body portion and engaging said nut for drawing said screen into firm engagement with said shell and projecting members on the bottom of said screen resting on said shell for supporting the weight of the screen against downward movement.

7. A guard for an automobile radiator comprising a screen having a frame thereabout of the size and shape conforming to that of the radiator shell, anchoring means therefor comprising a plurality of nuts having projections for engaging the edge of the inner portion of the shell, a plurality of screen engaging members, screws extending through said members and engaging said nuts and a plurality of projecting members on the bottom of said frame resting on said shell for supporting the weight of said guard.

8. A guard for an automobile radiator comprising a screen having a frame thereabout of the size and shape conforming to that of the radiator shell, anchoring means therefor comprising a plurality of nuts having pro-

jections for engaging the edge of the inner portion of the shell, a plurality of screen engaging members each comprising a body portion extending through a mesh of the screen and provided with inwardly presented channels for engaging the wires adjacent thereto, and screws extending through said members and engaging said nuts for retaining said guard in firm engagement with the shell.

9. A guard for an automobile radiator comprising a screen having a frame thereabout of the size and shape conforming to that of the radiator shell, anchoring means therefor comprising a plurality of nuts having projections for engaging the edge of the inner portion of the shell, a plurality of screen engaging members each comprising a body portion extending through a mesh in the screen and provided with inwardly presented channels on two of its opposite sides for engaging two of the wires forming the mesh, screws extending through said members and engaging said nuts and projecting means associated with the bottom of the frame and resting on the inturned portion of said shell for supporting the weight of said guard.

10. Anchoring means for supporting a member on an automobile radiator shell which comprises a nut having a flange for engaging the inner edge of the shell, a screw extending through said member for registering with said nut and for drawing the member into engagement with said shell and means on the bottom of said members associated with said shell and supporting the member against outward and downward movement.

11. Anchoring means for supporting a member on an automobile radiator shell which comprises a plurality of nuts having flanges for engaging the inner edges of the shell, a plurality of screws extending through said member for registering with said nuts for drawing the member into engagement with said shell and a plurality of projections on said member for engaging the shell and for supporting the member against downward movement.

12. Anchoring means for supporting a member on an automobile radiator shell which includes a plurality of nuts having flanges for engaging the inner edges of the shell, a plurality of screws extending through said member for registering with said nuts for drawing the members into engagement with said shell.

13. Anchoring means for supporting a member on an automobile radiator shell which comprises a plurality of nuts having flanges for engaging the inner edges of the shell, a plurality of screws extending through said member for registering with said nuts for drawing the member into engagement with said shell and a non-marring material

provided on the inner periphery of said member.

14. Anchoring means for supporting a member on an automobile radiator shell which comprises a plurality of nuts having flanges for engaging the inner edges of the shell, a plurality of screws extending through said member for registering with said nuts for drawing the member into engagement with said shell and a non-marring material provided on the inner periphery of said member and extending inwardly of the metal edge thereof to engage said shell in such manner as to support the weight of said member.
